ELECTRIC HAND AND HAIR DRIER

George S. Clemens, Evanston, and
James Teague, Chicago, Ill.

Application March 1, 1949, Serial No. 1,148

Term of patent 14 years

(CL. D86—10)

To all whom it may concern:

Be it known that we, George S. Clemens and James Teague, citizens of the United States, residing at 1028 Judson Avenue, Evanston, Illinois, and at 230 E. Ohio Street, Chicago, Illinois, respectively, in the county of Cook and State of Illinois, have invented a new, original, and ornamental Design for an Electric Hand and Hair Drier, of which the following is a specification, reference being had to the accompanying drawing, forming part thereof.

In the drawing; Figure 1 is a top plan view of an electric hand and hair drier, showing our new design; Figure 2 is a front elevational view thereof; Figure 3 is a bottom plan view; and Figure 4 is an end elevational view in which the unit is positioned for use as a hand drier. Figure 5 is a view similar to Figure 4, but showing the casing and nozzle inverted in respect to Figure 4, and in position for hair drying.

We claim:

The ornamental design for an electric hand and hair drier, as shown.

GEORGE S. CLEMENS.
JAMES TEAGUE.
